UNITED STATES PATENT OFFICE.

OTTO BAKER, OF SPARKILL, NEW YORK.

TRAP FOR RETURNING WATER OF CONDENSATION.

1,104,954.

Specification of Letters Patent.

Patented July 28, 1914.

Application filed December 2, 1912. Serial No. 734,608.

To all whom it may concern:

Be it known that I, OTTO BAKER, a citizen of the United States, residing at Sparkill, in the county of Rockland and State of New York, have invented certain new and useful Improvements in Traps for Returning Water of Condensation; and I do declare the following to be a full, clear, and exact description of the invention, such as will enable others skilled in the art to which it appertains to make and use the same.

This invention relates to water distribution, and more especially for feeders of that type which pass the water of condensation back to the boiler or hot well; and the object of the same is to produce a trap for this purpose having automatically operated valves for controlling the flow of water and accomplishing the end desired.

Details of the invention are set forth in the following specification and illustrated in the drawing which shows a diagrammatic elevation of the controller, receiver, the cylinders wherein condensation occurs, and the pipes; and the drawing also shows the valve mechanism in elevation, and the actuating mechanism therefor.

I will say at the beginning that my improved trap is shown in the accompanying drawings as applied to dryers or cylinders C, herein illustrated as disposed in several groups or banks, although I reserve the right to apply it to any device or devices herein typified by the cylinders C and in which drying is done by means of superheated steam. It is well known that such steam when hot and dry is an excellent medium for drying purposes, but it cools rapidly and eventually condenses, and of course the water of condensation will not dry anything. My improved trap is intended for removing this water of condensation from the various cylinders and driving it back to the hot well or water heater of the boiler (not shown) by means of steam pressure of about fifty pounds, taken preferably from the same boiler which supplies the superheated steam to the cylinders.

It will be obvious that details of construction, other than hereinafter set forth, are not necessary to carry out the system; and therefore the general diagrammatic view illustrated in the drawings will now be described.

The drying cylinders C are here shown

as arranged in groups or banks, and one end 1 (here the nearmost end) of each is connected by an outlet pipe 2 with a drain pipe 3. The drain pipes 3 from the several groups of cylinders C lead along proper courses, each through a control valve 4, and finally they deliver the water of condensation into a receiver or tank 5 which is preferably of considerable size and cylindrical and upright as shown. From the bottom of this tank leads an outlet pipe 6, through a suitable check valve 7 and across the head of a T-coupling 8, thence through another check valve 9 having an adjustable weight 70 9', and along a pipe 10 to the hot well of the boiler (not shown), and the stem of said T-coupling 8 is connected with the lower end of an upright cylindrical controller 11 standing alongside the receiver 5 but internally disconnected therefrom excepting through the pipe 6 and the check valve 7 as described.

The controller 11 contains a guide 12 in which moves an upright rod 13 standing along the axis of the controller body and extending through an opening in its dome-shaped head; and on this rod between stops 15 and 16 attached thereto moves a nipple 17 depending from the center of a float 18 which is of inverted cup-shape and has a surrounding flange 19 fitting loosely within the body 11. It follows that when water rises through the T-coupling 8 beneath said float, air is trapped within the latter between the nipple and flange, and the result is that as the water level rises the float rises and its nipple slides upward along the rod 13 until it contacts with the uppermost stop 15 when the rod will be raised by the float; 90 on the other hand, as the water level falls, the float falls until its nipple strikes the lowermost stop 16 when the rod will be moved downward with the float. Externally of the casing 11 and above its dome-shaped head, this rod carries two other stops 20 and 21.

The water of condensation which accumulates within the receiver and controller is ejected from the same by means 105 of steam pressure from the boiler (not shown) which we will assume is set at about fifty pounds, and for the purpose of forcing the water out of the pipe 10 and through the relief valve 9, the steam is admitted to 110 the controller through a pipe 22 having an inlet valve 23. The character of this valve

is unimportant, but it is shown as capable of being opened by raising a lever 24, and it is important that when the steam is being admitted to the controller the steam-outlet pipe 25 therefrom should be closed by its valve 26 which is shown also as actuated by a lever 27. The pressure of the steam within the controller drives out the water therein, which passes down through the T-coupling 8, closes the check valve 7 to the left, and is sufficient to open the check valve 9 to the right, so that the water flows to the hot well. On a reversal of the position of the two valves 23 and 26, the inlet of live steam to the controller is cut off and this steam is permitted to pass out the pipe 25 which leads to a T-coupling 29, downward from which extends a pipe 28 whereby the water of condensation which may arise throughout this course can be carried through a check valve 30 and into the water outlet pipe 6 whence it finds its way to the hot well through the course above described. But the outflowing steam—now relieved of its pressure and of much of its heat and therefore which we may well call vapor—is carried upward from the T-coupling by a pipe 31 and into the first of the series of cylinders, here marked C', which I propose to give over entirely to the work of condensing vapor as it will condense about three times as much as any other cylinder. The outlet for the water of condensation from this cylinder is through a pipe 32 to a drain pipe 33 which leads back to the hot well in a manner not necessary to illustrate.

The specific mechanism which I employ for simultaneously opening the steam inlet valve 23 and closing the steam outlet valve 26, or the reverse, forms an important feature of this invention, and I call it the valve actuator. The numeral 40 designates a substantially horizontal headed cylinder in which is a globular weight 41 adapted to move therein between its heads 42 and 42, and 43 is a disk-like hub on which this cylinder is supported over a pivot 44, the hub having two arcuate slots 45 struck around its center as shown. In each slot is adjustably secured a stub stop, formed preferably in the shape of shaft 46, and one stop underlies the lever 24 of the valve 23 while the other roller underlies the lever 27 of the valve 26. From one end of said cylinder projects a fork 49 which straddles the rod 13 between its stops 20 and 21. When now the float rises within the controller, the stop 21 eventually lifts the fork and tilts the actuator around its pivot so that the ball rolls to the left end of the cylinder 40, and the lever 24 of the steam inlet valve 23 is raised to open said valve and admit the steam at fifty pounds pressure. Meanwhile the left hand roller permits the descent of

the lever 27 of the steam outlet valve 26, which lever is weighted as shown at 27'; and the action above described takes place. After sufficient water has been expelled from the receiver and controller to permit the float to fall, the descent of the rod 13 causes the uppermost stop 20 to draw downward on the fork at one end of the cylinder 40, the latter rocks the disk around its pivot, and a reverse action takes place so that the steam inlet valve 23 is closed by the weight 24' on its lever 24, and the steam outlet is opened. 70 75

When the steam has been practically all exhausted from the controller 11, said mechanism acts to again open the steam inlet valve 23 and close the steam outlet valve 26, and the action is repeated; but as soon as the steam pressure closes the check valve 7 there is no outlet for the water of condensation at the bottom of the receiver 5, and therefore the water flowing into the receiver from the various drain pipes accumulates within it. The result is that the air above this water, which we may also call vapor, must be handled, and for this purpose I provide an outlet pipe 50 leading upward to a header 51 which may be connected through a pipe 52 and hand valve 53 with the first cylinder above mentioned 90 95 although said cylinder C' will probably be working to its full capacity to handle the water of condensation from the exhausting steam. I would therefore connect the header by another pipe 54 and a hand valve 55 with the second cylinder C² of the series, and give over this cylinder as well as the first cylinder C' for handling the condensed vapor; and the water of condensation from this cylinder may lead through an outlet pipe 56 into the drain pipe 33 and thence into the hot well as above described. If the live steam fed through the pipe 22 into the controller is under a greater pressure or temperature than normal, or if for any reason its condensation occurs more rapidly than the first cylinder C' can handle, by opening the valves 53 and 55 the second cylinder C² can be thrown into connection with the first one through the header 51, 100 105 110 115 and act with it to condense the steam as well as to condense the vapor arising through the pipe 50. In other words, if the plant be large, I give over the first two cylinders which will be the coolest of the series for condensing what might be called vapor. In like manner I may give over the cylinders, of the next group, herein numbered C³ for the use of handling the exhaust steam from the engine (under about fifteen pounds pressure) but this need not be described in detail. 120 125

Thus it will be seen that I have produced a machine having details of construction whereby the live steam led into the pipe 22 130

alternately ejects the water of condensation from the controller and forces it back to the hot well—then cuts itself off at the inlet and opens up the outlet so that its lower end 5 draws in another charge of the water of condensation from the receiver in which it has been meanwhile accumulating. The action is entirely automatic, and the various hand valves in the inlets to and outlets from 10 the several cylinders will doubtless be under control of workmen who are quite remote from this machine which I would by preference locate in the basement of the building and near the boiler.

15 What is claimed as new is:

1. An upright cylinder having inlet and outlet openings, valves controlling them, pivoted levers connected with the valve stems and projecting toward each other, and 20 weights for moving said levers to normally close said valves; combined with a centrally pivoted disk disposed between said levers and having arcuate slots in its opposite sides struck around its pivot, stops adjustably 25 mounted in said slots below the levers, a normally horizontal track carried by and across the upper edge of said disk, a moving weight on said track, and means for turning the disk on its pivot and swinging the track 30 over said pivot by the rise and fall of water within said cylinder.

2. An upright cylinder having inlet and outlet openings, valves controlling them, pivoted levers connected with the valve stems and projecting toward each other, and 35 weights for moving said levers to normally close said valves; combined with a centrally pivoted disk disposed between said levers and having arcuate slots in its opposite sides struck around its pivot, stops adjustably 40 mounted in said slots below the levers, a

normally horizontal track carried by and across the upper edge of said disk, a moving weight on said track, a fork projecting from one end of the track, a rod slidable vertically in guides throughout the length of 45 said cylinder and projecting above its top and through said fork, stops on the rod above and below the fork, other stops on the rod within the cylinder, and a float mounted 50 in the latter and loosely surrounding the rod between the last-named stops, for the purpose set forth.

3. An upright cylinder having inlet and outlet openings, valves controlling them, 55 pivoted levers connected with the valve stems and projecting toward each other, and weights for moving said levers to normally close said valves; combined with a disk standing in a vertical plane between said levers and pivoted on a support at one side of 60 said cylinder, the disk having arcuate slots on opposite sides of its pivot, stops adjustably mounted in said slots beneath the free ends of said levers, a substantially horizontal cylinder fixed across the upper edge of 65 said disk and having a fork projecting from one extremity, a rolling ball weight within said cylinder, a vertically movable rod within the first-named cylinder, means for controlling its position by the level of water 70 therein, the upper end of the rod projecting through said fork, and stops on said end above and below the fork, for the purpose set forth.

In testimony whereof I have hereunto set my hand in presence of two subscribing witnesses.

OTTO BAKER.
